CLAIM

We claim the ornamental design for the AC adapter unit enclosure, as shown and described.

DESCRIPTION

FIG. 1 is a front, top, and right side view showing our new design for an AC adapter unit enclosure;

FIG. 2 is a left side elevational view thereof;

FIG. 3 is a rear elevational view thereof;

FIG. 4 is a bottom elevational view thereof; and,

FIG. 5 is a front, top, and right side view showing an alternative embodiment of our new design for an AC adapter unit enclosure.
